SEALED PACKAGE

Howard G. Allen, Niagara Falls, N. Y., assignor,
by mesne assignments, to Boston Wire Stitcher
Company, Warwick, R. I., a corporation of
Maine

Application December 26, 1931
Serial No. 533,237

8 Claims. (Cl. 229—5.7)

This invention has to do with packaging articles, and it relates particularly to providing sealed containers for perishable articles such as edible articles or the like. The invention is directed particularly towards the provision of a sealed container which may have a curved formation. The invention is particularly applicable to pie containers, and for the purpose of disclosing the invention the same is shown and described herein in connection with a container for pies, or similar articles, but it should be understood that the invention is useful for packaging other articles of pastry such as cake or the like, or any other object or objects.

One environment for the invention is in conjunction with pie plates or pie containers which are usually of fibrous material and in which pies are held and sold to the trade. To seal the pie in the container a covering over the same may be provided of relatively thin material, such as cellophane or thin paper or the like which advantageously may be substantially transparent. Difficulties present themselves in securing such a thin covering material to the pie plate or container. In accordance with the present invention an element is utilized in cooperative relation with the peripheral edges of the pie plate and secured to the pie plate with portions of the thin sealing material disposed between the element and edge portions of the plate. With this arrangement the peripheral edges of the covering are securely held by being engaged between the element and edges of the plate. The element may be secured to the plate as by means of stitches and rivets or other penetrating devices.

The element when used with a container of circular form may, in its final form, be ring-like; it may be used, however, with containers of diverse shapes such as, for example, square or otherwise multisided, or oval, or the like. However, it is advantageous to apply a word to this element and it is termed herein a "ring", it being understood that such term is intended to describe the element when, in its final form, it is square, oval, or the like, as well as when it is circular. The particular formation of the holding ring is an important feature, and the present invention contemplates provision of such a ring which can be made cheaply with substantially no waste of material. For example, if the rings be cut from sheet-like material there is an immense wastage; the ring of the present formation may be formed from strip material fashioned so that one edge is curved on a radius shorter than the other, thus to effect the curving formation. This may be

accomplished by making one edge irregular or corrugated in shape, and in order to maintain such shape an additional element of metal or the like may be employed, which has sufficient rigidity to keep the corrugated edge of the ring in such 60 corrugated or irregular shape.

In the accompanying drawings:

Fig. 1 is a plan view of a container made in accordance with the invention.

Fig. 2 is an enlarged sectional view taken substantially on line 2—2 of Fig. 1.

Fig. 3 is an enlarged detailed view of a portion of the edge of the container.

Fig. 4 is a section taken on line 4—4 of Fig. 3.

Fig. 5 is a sectional view illustrating a modified form.

Fig. 6 is a sectional view illustrating a further modified form.

Fig. 7 is a sectional view illustrating a modified form of the invention.

Fig. 8 is a view illustrating another modified form.

Fig. 9 is a plan view of a completed rim element as it may be furnished to the trade.

Fig. 10 is a view of a drum type container with 80 which the invention may be utilized.

Fig. 11 is an enlarged sectional view taken through a rim on the drum.

Fig. 12 is a perspective of a drum rim which may utilize the invention.

The pie plate or container may be of the usual form and it may be of ground wood pulp or the like formed into shape while in moist condition and dried under pressure. It may have a bottom portion 1, a circular side wall 2, and a peripheral flange 3. This flange may be more or less creased as at 4 to give the same an angular formation in cross section increasing its strength and rigidity. The body of the article or pie is disposed therein, as illustrated at 5.

Heretofore, pies have been handled and sold to the trade in an uncovered container substantially as just described. In order to seal the container, a cover element 10 may be placed over the container, and this advantageously may be of relatively thin material as above pointed out. Where the container is circular in form, as illustrated in Fig. 1, the cover 10 likewise may be circular and preferably of a diameter substantially equal to the overall diameter of the plate so that its peripheral edges lap over the flange 3. The peripheral edges of the cover may be utilized for holding the same in place as by securing the peripheral edges to the plate flange. For this purpose a ring like element may be disposed around the periph-

110

eral edges of the container over the cover, said ring like element being generally indicated at 11. This member preferably comprises a strip of material of paper, jute or the like, folded upon itself 5 so as to provide a leg 12 and a leg 13 joined by a bight portion 14. This member is preferably shaped so that it is angular in cross section, as illustrated in Fig. 4, thus, to fit the flange 3, with the edges of the cover interposed between the 10 ring and flange. In order to provide the curved formation of the ring, the inside edge may be corrugated or otherwise irregularly shaped, as illustrated in Figs. 1 and 3, and preferably the bight portion is disposed so as to constitute the 15 inner peripheral edge.

The legs 12 and 13 may be secured together by a suitable adhesive or glue, and the ring may be disposed in such manner that its ends substantially abut, as illustrated in Fig. 1, thus forming 20 substantially a closed ring, or to overlap as shown in Fig. 9. In order to aid in the maintaining of the irregular formation of the inner edge, an additional element may be provided which may take the form of a metallic wire or strip 15 disposed preferably in the bight portion of the ring. This wire is preferably of a metal of sufficient 25 stiffness and rigidity so that the corrugations once formed will be substantially maintained thereby. The ring may be attached to the peripheral edges of the plate by means of securing devices penetrating the ring, the peripheral edge of the cover, and the flange of the plate. These 30 penetrating devices may be metallic and may be in the form of wire stitches. This manner of joining a container flange, cover and ring is shown 35 in application Serial No. 571,128, filed October 26, 1931, of which I am a joint inventor.

The invention contemplates modifications of the ring structure, and as shown in Fig. 5 the 40 structure comprises a strip of material bent upon itself to form leg portions connected by a bight portion, and the same is identified by the reference character 20, the legs of this form may be united by glue or the like but the reinforcing 45 metallic wire element is omitted. The bight portion lends some rigidity and strength to one edge, and this is the edge preferably to be corrugated or irregularly formed. The form shown in Fig. 6 is made up of two strips of material 21 and 22 glued 50 or otherwise secured together with a metallic or other reinforcing element 23 disposed between them, and located preferably in close proximity to one edge, this being the edge to be corrugated or irregularly formed.

55 It will be readily appreciated that if the ring is formed by cutting the same from a blank of material that there is an immense amount of waste. The present ring may be made up of straight strip material together with a piece of 60 wire for an insert with the material folded around the same, and with its opposing portions or legs glued together. This of course will result in a straight strip of material. To curve the same it is then corrugated along one edge to shorten 65 said edge, and where the flange of the pie plate is angular in cross section as shown, this strip may be similarly fashioned. The ring shown in Figs. 1 to 4 may be made by drawing the strip of material and wire from reels and progressively drawing the same through suitable mechanism such as rolls or dies for folding the paper strip around the wire, shaping and corrugating the same. In the case of the modified form shown 70 in Fig. 6 two strips of material may be drawn from reels with the wire properly positioned be-

tween them and then the strips may be secured together.

As regards the modified form shown in Fig. 7, it may be pointed out that this form bears a resemblance to that shown in Fig. 6 having the 80 two strips of material 20 and 21, but the metallic reinforcing element is not a wire round in cross section but is in the nature of a flat strip. Fig. 8 shows a single sheet of material folded upon itself to form the bight portion utilizing 85 a rather flat reinforcing element 25. Rim elements for containers may be made up in the desired shape, securely held in this shape and supplied to the trade for disposition around the rim of a container body. A circular rim element is 90 shown in Fig. 9 which is composed of the structure above the described. Its ends may be secured together in any desirable way, as for example, overlapping them as shown and securing them at the overlapped portions. This advantageously may be done by a metallic penetrating 95 element or stitch 26, although the overlapped edges may be fixed as by means of an adhesive or the like.

The invention lends itself for use in connection with drum type containers. Such a container is shown in Fig. 10 wherein the body is drum shaped which may be formed of a blank of fiber board or the like having a seam running from edge to edge, said body being illustrated 105 at 30. The drum may be closed by a head 31 of disk form where the drum is round in cross section. In order to secure the head to the drum a ring or rim is provided which, as shown in Fig. 11, may comprise two superimposed sheets 110 32 and 33, and these sheets may be integral with each end formed by a single ribbon folded upon itself to form a bight 34. The seam is fashioned to form a flange 35 which may overlie the outside edge of the drum, a top portion 36, and 115 an inside flange 37. Projecting radially inwardly from the flange 37 may be a flange 38. In order to properly form and obtain a curvature, the flange 38 may be corrugated, as illustrated in Fig. 12, and for this purpose a reinforcing metallic element 39 may be used. Likewise the reinforcing metallic element 40 may be employed in the flange 37. A reinforcing metallic element 41 may be used in the bight portion. The head 31 may be secured in flange 39 as by means 125 of penetrating devices such as stitches or the like 42, and then the head comprising member 31 and ring may be secured to the end of the drum container by penetrating devices such as 130 stitches 43 taken through the flange 35, the end 135 portion of the body wall and the flange 37. With these reinforcing metallic members the ring as a whole may be made from relatively light fibrous stock, the metallic reinforcing elements serving to provide requisite rigidity and holding the same 135 in shape.

It is again to be emphasized that the invention is not limited to containers of a circular formation, as rim devices composed of a strip of suitable material, such as paper or other fibrous substance, embodying the reinforcing metallic element may be employed with containers of all shapes whether they be square or otherwise multi-sided.

I claim:

1. A container for an article of pastry or the like comprising a holder of circular form having a side wall and adapted to hold an article, a covering of thin flexible material the peripheral edges of which overlap parts of the side wall, a 140

- strip of fibrous material over the peripheral edge of the covering, said strip having an irregularly shaped inner edge to render the same of curved formation, a metallic reinforcing means for maintaining such irregular shape in said strip, and means securing the strip to the side wall. 5 the like, comprising a container body having side walls, a flange projecting outwardly from the side walls, a sheet of sealing material positioned so that its edges overlie said flange, a strip of material folded upon itself and positioned around the flange with the bight portion innermost, a reinforcing element located in the bight of the strip with the bight edge of the strip and the reinforcing element corrugated, said reinforcing element serving to maintain said corrugated shape, and means securing the strip to the flange. 80
2. A container for an article of pastry or the like comprising a holder of circular form having a side wall and adapted to hold an article, a flange projecting from the side wall, a covering of thin flexible material circular in form having its peripheral edges overlying the flange, a strip of fibrous material disposed over the flange and peripheral edges of the covering material, said strip being irregularly shaped on its inner edge to render the same of curved formation, a metallic reinforcing means secured to the strip along its inner edge for maintaining such irregular shape, and means securing the strip to the flange. 10 85
- 15 3. A container for an article of pastry or the like comprising a holder of circular form having a side wall and adapted to hold an article, a flange projecting outwardly from the side wall, a sheet of covering material of circular form having its peripheral edges overlying the flange, a strip of fibrous material over the peripheral edge of the covering material, said strip of material being corrugated on its inner edge whereby the same is given a curved formation, a strip of metal 20 extending along the inner edge of said curved strip and similarly corrugated and serving to maintain the corrugations in the first mentioned strip, and means for securing the first mentioned strip to the flange. 90
- 25 4. A container for an article of pastry or the like comprising a holder of circular form having a side wall and adapted to hold an article, a flange projecting outwardly from the side wall, a sheet of covering material of circular form having its peripheral edges overlying the flange, a strip of fibrous material over the peripheral edge of the covering material, said strip of material being corrugated on its inner edge whereby the same is given a curved formation, a strip of metal 30 extending along the inner edge of said curved strip and similarly corrugated and serving to maintain the corrugations in the first mentioned strip, and means for securing the first mentioned strip to the flange. 95
- 35 5. A sealed container for perishable articles or the like, comprising a container body having side walls, a flange projecting outwardly from the side walls, a sheet of sealing material positioned so that its edges overlie said flange, a strip of material folded upon itself and positioned around the flange with the bight portion innermost, and a metallic wire-like element disposed in the bight portion of the strip with the bight portion and wire-like element corrugated, said wire like element serving to maintain the corrugated shape, and means penetrating the strip, the edges of the sealing material, and the flange, for securing the said penetrated parts together. 100
- 40 6. As a new article of manufacture, a rim device for a container comprising a strip of fibrous material curved substantially edgewise into a closed substantially circular area with its ends in close proximity, the inner edge of the strip being corrugated, a metallic reinforcing strip associated with the inner edge and similarly corrugated serving to maintain the corrugated shape, and means securing the ends together. 105
- 45 7. As a new article of manufacture, a rim reinforcement for a pie container or the like having a generally horizontal rim comprising superimposed layers of fibrous strip material with said layers united to each other, a metallic wire running the length of the strip near one edge thereof and confined between the united layers of fibrous strip material, said reinforcement being arranged to be corrugated on one edge and fashioned substantially into circular form by being bent edgewise so as to fit over the said rim on the 110 container, the fibrous strip material having insufficient rigidity to maintain the corrugated form along one edge and said wire being disposed along the edge to be corrugated to reinforce the same and to maintain said corrugated shape. 115
- 50 8. As a new article of manufacture, a rim reinforcement for a pie container or the like having a generally horizontal rim comprising superimposed layers of fibrous strip material with said layers united to each other, a metallic wire running the length of the strip near one edge thereof and confined between the united layers of fibrous strip material, said reinforcement being arranged to be corrugated on one edge and fashioned substantially into circular form by being bent edgewise so as to fit over the said rim on the 120 container, the fibrous strip material having insufficient rigidity to maintain the corrugated form along one edge and said wire being disposed along the edge to be corrugated to reinforce the same and to maintain said corrugated shape. 125
